(57) **CLAIM**

The ornamental design for a decorative bow gift box, substantially as shown and described.

DESCRIPTION

FIG. 1 is a top plan view of the decorative bow gift box;

FIG. 2 is a left side elevational view thereof;

FIG. 3 is a right side elevational view thereof, the other side view being similar;

FIG. 4 is a front side view thereof;

FIG. 5 is a rear elevational view thereof;

FIG. 6 is a bottom plan view; and,

FIG. 7 is a plan view of the decorative bow gift box prior to being folded to form the entire box.

The broken line showing in FIGS. 6 and 7 represent fold lines.
